ATTORNEY.

UNITED STATES PATENT OFFICE.

HORACE G. HANCOCK, OF NEW BRITAIN, CONNECTICUT, ASSIGNOR TO NORTH & JUDD MANUFACTURING COMPANY, OF NEW BRITAIN, CONNECTICUT, A CORPORATION OF CONNECTICUT.

BUCKLE.

Application filed July 26, 1923. Serial No. 653,834.

To all whom it may concern:

Be it known that I, HORACE G. HANCOCK, citizen of the United States of America, residing at New Britain, in the county of 5 Hartford and State of Connecticut, have invented certain new and useful Improvements in Buckles, of which the following is a specification.

This invention relates to a buckle and 10 especially to a method of assembling the parts thereof by which reduction in the cost of production can be accomplished without in any effect impairing the strength or appearance of the buckle.

15 In the drawing accompanying and forming part of the present specification I have disclosed a way of carrying the method into effect which will be fully set forth to enable those skilled in the art to practice the 20 method. Clearly, I am not restricted to such disclosure. I may depart therefrom in several particulars within the scope of the invention covered in the claim superseding said description.

25 Referring to said drawing:

Fig. 1 is a top plan view of a buckle made in accordance with the invention.

Fig. 2 is a longitudinal central section.

30 Fig. 3 is a top plan view of a sliding grip blank with the ears bent into operative relation.

Fig. 4 is an end view of said blank with the ears bent to facilitate assembling to frame of buckle.

35 Like characters refer to like parts throughout the several views.

In carrying the method into effect I employ a frame, such as that denoted by 2. The frame is rectangular and comprises 40 two elongated side bars 3 and 4 and two end bars as 5 and 6 forming a rectangular structure. One end of the buckle frame 2 is outwardly bent, as shown in Fig. 2.

45 In addition to the end bars 5 and 6 the buckle involves two intermediate bars, as 7 and 8, the intermediate bar 7 being flattened upon its upper side, as shown in Fig. 2, and the flattened face being in a plain parallel to the flattened face of the 50 rear end bar 5 and being under the lower surface of the sides 3 and 4 to permit an easy motion of the sliding grip blank. The

bars 5 and 7 are spaced apart for a purpose which will hereinafter be set forth.

The bar 8, as shown, has looped to it 55 one end of the belt 9. Inside the frame I place a slide as 10. The slide is practically rectangular in construction. It has at one end an elongated slot 11 and at the other end lugs or ears 12 which are initially bent downward, as shown in Fig. 4, to permit the slide 10 being inserted between the side bars 3 and 4 of the frame and between the cross bars 5 and 7. After the slide 10 is thus positioned the lugs or 60 ears 12 are straightened, as shown in Figs. 1 and 2 to engage the under side of the side bars 3 and 4.

It is thought that the method of assembling the parts will be at once understood, 70 but nevertheless I believe it proper to briefly note that initially the gripping blank 10, with the ears or lugs 12, in the position they are shown as occupying in Fig. 4, is passed upwardly between the cross bar 7 and the 75 end bar 5 and it is then laid flatwise against the flattened faces of the bars 5 and 7 following which by the aid of a proper tool the ears 12 are flattened outward and are projected under the side bars 3 and 4 to permanently connect the two members. 80

One end of the belt is attached to the cross bar 8 and the opposite end is threaded through the slot 11 and overlies the slide 10 and the belt is then passed under the 85 end bar 6. A pull on the belt will cause the gripping member or slide 10 to press the belt firmly against the end bar 5 of the frame.

What I claim is:

90 A method of making a buckle, involving the use of a rectangular frame having a bar between the ends thereof and also involving a grip having lugs at opposite sides, said method comprising passing the 95 grip into the frame, then turning it in the frame, and then bending the lugs of the grip at right angles to their original position which is in transverse alignment with the body of the grip to abut against the side 100 bars of the frame.

In testimony whereof I affix my signature.

HORACE G. HANCOCK.
